Attorney

UNITED STATES PATENT OFFICE.

FRANK J. J. EMMERICH, OF SALINA, KANSAS.

MILK-BOTTLE RECEIVER AND RETAINER.

Application filed June 16, 1924. Serial No. 720,272.

To all whom it may concern:

Be it known that I, FRANK J. J. EMMERICH, a citizen of the United States, residing at Salina, in the county of Saline and State of Kansas, have invented a new and useful Milk-Bottle Receiver and Retainer, of which the following is a specification.

The object of the invention is to provide a sanitary milk-bottle receiver and container and the object thereof is to so construct a device of this character that as to fully protect a milk-bottle or the like against contamination by flies, dust and the like as well as to avoid all possibility of its being upset and protect it also against the weather.

Another object of the invention is to provide a device of this character which will prevent the loss of milk and money and which may be so constructed as to present a pleasing appearance adapting it for use in the front of the house, without being objectionable.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a vertical section of the container with the top and the parts co-operating therewith shown in open position, which position they assume when a bottle is to be placed in or removed from the container; and

Fig. 2 represents a similar view with the container closed and the bottle shown housed therein;

In the embodiment illustrated a container is shown in the form of a box 1 having a hinged lid 2 with a bottle support or carrier 3 connected with its inner face by means of a bracket 4. The bracket 4 is fixedly secured to the inner face of the lid 2 and pivotally connected with the bottle support 3. As shown both the bottle support and the bracket are U-shaped in form, the bracket being inverted and the arms 5 thereof pivotally connected with the free ends of the arms 6 of the stirrup-like hanger.

The U-shaped bottle support or hanger 3

is preferably constructed of strap iron of a width sufficient to support a milk bottle.

A stop rod 7 has a laterally extending finger 8 at its upper end and slides loosely in an aperture 3^a formed in the bottom of the holder or support 3. This rod 7 has a laterally extending arm 9 at its lower end which is pivotally mounted in one of the side walls of the container 1 as is shown clearly in Fig. 2. This rod 7 is designed to operate as a stop to prevent the carrier 3 from throwing the bottle out of the container.

A cleat 10 is arranged transversely across the front of the container 1 near its upper end and is designed to form a shelf or seat onto which the bottle is shifted by the carrier when it reaches a predetermined point and thus prevents the bottle from falling back into the box and where it is held until manually removed.

A flange 11 is arranged between the upper end of the container or box 1 and the lid 2 and operates to keep out dust, flies and the like.

The bottom 1^a of the container 1 has a projecting flange 11 equipped with screw holes as 12 for securing the container to a support such as to a porch floor or a step.

It will be obvious that the carrier 3 as shown in dotted lines in Fig. 1 does not rest on the bottom of the container but depends from the inner face of the lid 2 and is designed to receive the bottle D the weight of which pulls the lid 2 down and holds it closed preventing accidental opening or opening by cats, dogs and the like.

In the use of this container it may be placed in any desired place convenient to the milk-man and being decorated or ornamented to the suitable or desired manner will present an attractive rather than an objectionable appearance. A coin clip 13 is attached to the inner face of the lid 2 and may be used to hold money to pay for the milk or to hold a note addressed to the milk man. When a bottle is placed in the carrier 3 and the lid 2 swung into closed position as shown in Fig. 2 the lid will be securely held closed and will protect the milk and the bottle or jars, from the sun, from contamination by flies, dust and the like as well as to prevent all possibility of its being upset by dogs, cats or children.

It is of course understood that empty

bottles are also placed in the container at night or other times so that when opening the lid the milk man may take out the empty and replace it with a full bottle.

5 I claim:—

1. A container for milk bottles and the like having a bottle receiving and supporting ledge, and equipped with a hinged lid having a bottle carrier suspended from its 10 inner face, means connecting the carrier with the lid to adapt the carrier to swing into an inclined position when the lid is opened and to kick the bottle carried thereby onto said supporting ledge.

15 2. A container for milk bottles and the like having a hinged lid, a bracket secured to the inner face of said lid, a bottle carrier pivotally carried on said bracket, and means housed at all times in the container and connected with said container and with said carrier to limit the outward swinging movement of the carrier.

25 3. A container of the class described including a hinged lid, a carrier pivotally mounted on the inner face of said lid, and a stop for limiting the outward swinging movement of the carrier, said stop being completely housed at all times within the 30 container and comprising a rod extended loosely through the carrier and having a lateral finger to limit its sliding movement, said rod having its other end pivotally engaged with one of the walls of the container.

35 4. A container of the class described com-

prising a hinged lid, an inverted U-shaped bracket and a U-shaped carrier having its free ends pivotally connected with the free ends of the bracket whereby when the lid is opened the carrier is swung into an inclined position, and a stop for limiting the 40 outward swinging movement of the carrier comprising a rod extended loosely through the bottom of the carrier and having a lateral finger to limit its sliding movement, said rod having a laterally extending arm at 45 the other end pivotally mounted in one of the side walls of the container.

5. A container of the class described having a hinged lid, an inverted U-shaped bracket secured by its cross bar to the inner 50 face of said lid, and a U-shaped carrier having its free end pivotally connected with the free ends of the bracket whereby, when the lid is opened the carrier is swung into an inclined position, and a laterally and inwardly extending projection carried by 55 said container in position to receive the bottle when the carrier reaches the limit of its outward movement, whereby the bottle is prevented from dropping back into the container.

In testimony that I claim the foregoing as my own, I have hereto affixed my signature in the presence of two witnesses.

FRANK J. J. EMMERICH.
